UNITED STATES PATENT OFFICE.

JAMES M. WILSON, OF ROCHESTER, NEW YORK.

AUTO-LOCK.

1,280,348.

Specification of Letters Patent. Patented Oct. 1, 1918.

Application filed January 5, 1918. Serial No. 210,585.

To all whom it may concern:

Be it known that I, JAMES M. WILSON, a citizen of the United States, residing at Rochester, in the county of Monroe and State of New York, have invented certain new and useful Improvements in Auto-Locks, of which the following is a specification.

The object of this invention is to provide 10 a new and useful improvement in locks for automobiles.

This and other objects of the invention will be fully illustrated in the drawings, described in the specification and pointed out 15 in the claims at the end thereof.

In the drawings,

Figure 1 is a top plan view of the steering wheel and lock,

Fig. 2 is a vertical section on the line 20 2X—2X of Fig. 3.

Fig. 3 is a section on the line 3X—3X of Fig. 2, looking up from below.

Fig. 4 is a section on the line 4X—4X of Fig. 2.

Fig. 5 is a side elevation of the locking bar.

In the accompanying drawings, like reference numerals indicate like parts.

In the drawings, reference numeral 1 indicates the casing for the steering column. At the top of the casing is provided a collar 2 which is stationary therewith and is clamped thereon. The collar is divided at 3 with a lap joint which permits its expansion 35 for the purpose of getting it in place and contraction for the purpose of fastening it in place. In the outer lap 4 a screw hole is provided; and in the inner lap 5 a slot is provided. Through these openings the 40 screw 6 is passed which engages with the casing 1 of the steering column by which the collar is held in place. On the collar is provided the lug 7 having an opening 8 therein, in which may be received the bolt 45 30 for the locking device.

Inside of the shell 1 is contained a series of hollow shafts as shown in cross section in Fig. 4, to the outer one of which is fastened the steering wheel 9, the steering wheel 50 and shaft revolving together. To the second and third hollow shafts are fastened the spark and throttle controls 10 and 11. On the inner shaft, which may be stationary, is supported the cap 12 which is independent 55 of and does not turn with the steering wheel or the controlling levers. On the top of the

cap 12 is formed a stud 13 which carries the base plate 14 on which the lock is mounted. On the base plate 14 is mounted a casing 15, on the top of which is provided the dial 60 plate 16, mounted to rotate within the stationary ring 17. The dial plate 16 is provided with a stem 18, which passes through the top of the casing 15 and has the plate 19 keyed to the bottom thereof.

Mounted to slide past the stem 18 between the casing 15 and the plate 19 is the bolt 20, which bolt is slotted at the right hand end as shown in Fig. 3 to straddle the stem 18, by which its movement to the right is 70 limited.

On the bottom of the plate 19 is carried a lug 21 which engages with a corresponding lug on the top of the tumbler 22. On the bottom of the tumbler 22 is carried another 75 lug which engages with a corresponding lug on the top of the tumbler 23. On the bottom of the tumbler 23 is a similar lug which engages with a corresponding lug on the top of the tumbler 24. The lugs on the top and 80 bottom of each tumbler are preferably formed by a staple which passes through the holes in the tumbler and is left in position so that it projects on both sides of the plate. In this way a combination of tumblers is 85 provided all centered on the stem 18, which tumblers are controlled by the dial plate 16, in the manner in which similar tumblers are operated in the ordinary combination lock.

Each of these tumblers is recessed as indicated at 25. On the bolt 20 is provided a pawl 26 having a tooth 27 thereon which can engage with the recesses 25 provided in the tumblers. A spring 29 is provided for pressing the pawl 26 in one direction so that 95 the tooth 27 thereon will engage in the recesses 25 in the various tumblers when all of these recesses have been brought into a single line as is common practice in the operation of combination locks.

After the tumblers 22, 23 and 24 have been properly positioned and the pawl 26 and tooth 27 have made engagement with the tumblers as above described, the bolt 20 can be thrown back by the rotation of the 105 dial plate 16 in one direction holding the tumblers in engagement therewith fast against further rotation in that direction. By turning the dial plate in the other direction the bolt will be thrown forward and 110 the tumblers will be released for rotation in either direction.

Moving transversely of the casing 15 is the bar 30 having a T shaped head 31 with a recess 32 therein capable of receiving the bolt 20. When the bar 30 is in the position 5 shown in Fig. 2 the bolt 20 can be turned forward into engagement therewith and the bar 30 will then be locked in position with the combination being thrown off. The lower end of the bar 30 engages in the socket 10 8 in the lug 7 on the collar 2. The bar passes close to the hub of the steering wheel between the spokes of the steering wheel, preventing the rotation of the steering wheel except through a small angle of less than 15 20 degrees, which angle of rotation is not sufficient for steering the car. It also will interfere with the movement of the levers 10 and 11 and prevent the operation of the car through them as well.

20 When not in use for the purpose of locking the car, the bar 30 will be dropped down through the lug 7 out of place with its T-shaped head resting on top of the lug 7. When used to lock the car, it will be raised 25 up between the spokes of the steering wheel

with its T shaped head in place in the casing 15 after which the bolt 20 can be thrown forward, locking it in place and locking the car.

I claim:

1. In an automobile locking device, the combination of a casing for the steering column, having a steering wheel on the top thereof, a lug rigidly fastened on the steering column below the wheel, a lock mounted above the wheel, a locking bar extending from said lug between the spokes of the wheel to the lock above the wheel, said bar being fastened in place by said lock. 30

2. A locking device for an automobile having a bolt and a casing, said locking device being mounted above the steering wheel, a lug rigidly fastened on the steering post casing below the steering wheel and a bar extending through said lug and through the 35 spokes of the steering wheel into the casing of the lock, said bar being fastened in place by the bolt of said lock. 40

In testimony whereof I affix my signature.
JAMES M. WILSON.
